VOLTAGE RECTIFYING CIRCUIT

Albert W. Friend, Collingswood, N. J., assignor
to Radio Corporation of America, a corpora-
tion of Delaware

Application November 28, 1945, Serial No. 631,434

5 Claims. (Cl. 321—15)

1

This invention relates generally to voltage rectifying circuits and more particularly to voltage rectifying and multiplying circuits employing phototubes as voltage rectifying devices.

Voltage rectifying and multiplying circuits for delivering high voltages of the order of 10 to 100 kilovolts to cathode ray, X-ray and electron microscope apparatus require the use of expensive, high-voltage-insulated transformers which are relatively large in size and uneconomical in view of the relatively low power delivered by the circuit, since such load devices usually require currents of less than one milliamper. Voltage multiplying circuits provide means for developing a unidirectional voltage greater than the peak alternating voltage of the source. Such circuits frequently are employed when such high voltages are required that it is impractical to utilize a transformer for developing the full output voltage, or when it is desired to derive sufficient output voltage to operate low power load devices from a line voltage source without the use of transformers. However, the use of conventional thermionic rectifier tubes in voltage multiplying circuits requires the use of high-voltage-insulated thermionic cathode transformer supply windings in order that the cathode heaters or thermionic cathodes of the several cascaded thermionic rectifiers may be operated at widely differing voltage levels with respect to the supply voltage source. Such conventional voltage multiplying circuits also require the use of power dissipating resistors in each cascaded stage of the circuit.

The instant invention contemplates the use of conventional high impedance phototubes to replace the thermionic rectifiers, and, if desired, the power dissipating resistors, of conventional voltage multiplying circuits. Thus, the high-voltage-insulated cathode energizing windings of such circuits may be eliminated with resulting economy and reduction of circuit size. The impedance of the vacuum type phototubes may be controlled selectively by means of radiation from a light source directed at each of the phototubes. The light source preferably should be of the incandescent type having high heat capacity so that the alternating current heating thereof may be filtered effectively to produce continuous, substantially constant intensity, illumination of the phototubes. Thus, for high voltage, low current load devices the only apparatus required for deriving suitably high load voltage from the power line is a plurality of phototubes serially connected in cascade with a plurality of capacitors in a manner whereby the voltage developed across

the several capacitors is effectively added and applied to the load circuit. The irradiating light source for the phototubes may be supplied directly from the alternating current source, or it may be connected thereto through a suitable low voltage transformer. If desired, light from the irradiating source may be impressed separately at the desired intensity on each of the phototubes by means of a plurality of light conduits comprising suitably shaped transparent rods of Lucite, glass or fused quartz, whereby the light may be directed substantially only upon the photo-sensitive elements of the phototubes.

Among the objects of the invention are to provide an improved method of and means for rectifying alternating voltages. Another object is to provide an improved voltage multiplying circuit. An additional object is to provide an improved voltage rectifying or multiplying circuit employing phototubes as voltage rectifying devices. A further object is to provide an improved voltage rectifying circuit employing phototubes as voltage rectifying and resistive devices. A still further object is to provide an improved voltage rectifying and multiplying circuit requiring no high-voltage-insulated transformer windings for energizing the rectifying devices. Another object is to provide an improved high voltage, low power voltage rectifier and multiplier circuit having selective control of circuit impedance. A further object is to provide an improved high voltage, low power rectifying and voltage multiplying circuit employing phototubes as voltage rectifiers and resistors, and including means for controlling the circuit impedance by selectively controlling the irradiation of the phototubes.

The invention will be described in greater detail by reference to accompanying drawings of which Figure 1 is a schematic circuit diagram of a conventional voltage multiplying circuit employing thermionic diodes as rectifying devices, Figure 2 is a schematic circuit diagram of a preferred embodiment of the invention, and Figure 3 is a schematic circuit diagram of a second embodiment of the invention. Similar reference characters are applied to similar elements throughout the drawings.

Referring to Figure 1 of the drawing, a conventional voltage multiplying rectifier circuit utilizing thermionic diodes as rectifying devices includes an input transformer 1 having its primary winding 3 connected to input terminals 5, 7 to which is applied an alternating voltage derived from a power line. The transformer 1 includes a secondary winding 9 providing the desired

voltage increase in view of practical transformer design characteristics. The voltage derived across the secondary winding 8 of the transformer 1 is applied to the anode of a first diode rectifier 11 and through a first capacitor 13 to the cathode of said first diode 11. The cathode of the first diode 11 is energized from a first low voltage secondary winding 15 of a filament transformer 17, the primary winding 19 of which is connected to the alternating current input terminals 5 and 7.

The anode of the first diode 11 is connected through a second capacitor 21 to the anode of a second diode 23 and to one terminal of a first resistor 25. The remaining terminal of the first resistor 25 is connected to the cathode of the first diode 11, and is also coupled through a third capacitor 27 to the cathode of the second diode 23. The cathode of the second diode 23 is energized from a second low voltage secondary winding 29 of the filament transformer 17.

Similarly the anode of the second diode 23 is connected through a fourth capacitor 31 to one terminal of a second resistor 33 and to the anode of a succeeding diode 35. The remaining terminal of the second resistor 33 is connected to the cathode of the second diode 23 and is coupled through a fifth capacitor 37 to the cathode of the succeeding diode 35. The cathode of the diode 35 is energized from a third low voltage secondary winding 39 of the filament transformer 17. The low voltage secondary windings 15, 29 and 39 of the filament transformer 17 require high voltage insulation between each other and from the primary winding 19 thereof, since the cascaded diode rectifiers are at increasingly high voltage levels with respect to each other and to the voltage source. The multiplied output voltage is derived from output terminals 41, 43 which are connected, respectively, to the cathode of the last diode 35 and to the grounded terminal of the high voltage secondary winding 9 of the first transformer 1.

In operation, the diodes 11, 23 and 35 each conduct on positive half cycles of the alternating potential applied to each of them. Thus, a voltage substantially equal to the peak voltage derived across the high voltage secondary winding 9 of the first transformer 1 is developed across each of the capacitors 13, 21 and 37. Since these capacitors are effectively connected in series relation, the voltages developed thereacross are effectively added and are applied to the output terminals 41 and 43, whereby the output voltage is substantially equal to the peak voltage developed across the high voltage secondary winding 9 of the transformer 1 multiplied by the number of cascaded diode rectifiers employed in the circuit. It should be understood that the first high voltage transformer 1 may be omitted if the additional voltage multiplication provided thereby is not required.

Figure 2 shows a circuit employing a plurality of alternately oppositely polarized radiation-responsive high impedance vacuum type phototubes 45, 47, 49, 51 and 53 which replace respectively the diodes and resistors 11, 25, 23, 33 and 35 of the voltage multiplying circuit described heretofore by reference to Fig. 1. Since the phototubes require no cathode excitation voltage, the filament transformer of the circuit of Fig. 1 is omitted. The high voltage developed across the secondary winding 9 of the input transformer 1 is applied to the serially-connected first phototube 45 and first capacitor 13 to develop thereacross a rectified voltage sub-

stantially equal to the peak voltage developed across the high voltage transformer secondary winding 9. Similarly the serially-connected second capacitor 21 and third phototube 49 develop across the third capacitor 27 a second voltage equal to the peak voltage across the transformer secondary winding 9. The second oppositely-polarized phototube 47 operates as a polarized resistor which completes the charging circuit of the third capacitor 27.

Similarly the fourth capacitor 31 and the fifth phototube 53 in conjunction with the oppositely-polarized fourth phototube 51 develop a voltage across the fifth capacitor 37 which is substantially equal to the peak voltage developed across the transformer secondary winding 9. Since the first, third and fifth capacitors 13, 27 and 37 are effectively connected in series, the output voltage developed across the output terminals 41 and 43 is equal to the sum of the capacitor voltages, and thus is equal to three times the peak voltage across the secondary winding 9. The conductivity of each of the phototubes is selectively controlled by means of an incandescent lamp 55 which irradiates each of the phototubes at the desired light intensity. The incandescent lamp 55 is energized from a low voltage secondary winding 57 of the transformer 1 or from any other suitable voltage source. Preferably the incandescent lamp 55 should have a filament of high heat capacity so that the alternating current heating thereof may be effectively filtered to minimize illumination ripple. The illumination may be controlled, for example, by means of an adjustable tap 59 on the low voltage secondary winding 57 of the transformer 1. The several phototubes also may be differently masked, not shown, to provide the desired control of illumination thereof for regulating the conductivity and impedance of each of the phototubes.

The circuit of Figure 3 utilizes resistors 25 and 33 in place of the oppositely-polarized second and fourth phototubes 47 and 51, respectively, of the circuit of Fig. 2. The operation of the circuit otherwise is identical to that of Fig. 2, with the exception that the light source 55 illuminates the phototubes 45, 49 and 53 through separate light conduits 61, 63 and 65, respectively. The light conduits 61, 63 and 65 may comprise, for example, suitably shaped solid rods of Lucite, glass or fused quartz whereby light from the source 55 may be directed substantially only upon the radiation-responsive cathodes of the individual phototubes. The intensity of illumination irradiating each phototube may be separately controlled by suitable masking of the phototube or light conduit in any manner well known in the art.

Thus, the invention disclosed and claimed herein contemplates the use of high impedance, vacuum type phototubes as rectifiers and resistors in voltage rectifying and multiplying circuits to provide an efficient, compact and economical circuit arrangement wherein the impedance or conductivity of the several phototubes may be selectively controlled by the intensity of illumination irradiating said phototubes. The improved circuits disclosed eliminate the necessity for expensive and bulky filament transformers which require high voltage insulation between transformer windings connected to each of the cascaded rectifiers of a voltage multiplying circuit.

I claim as my invention:

1. A voltage multiplying rectifier circuit com-

prising, in combination, a source of alternating potential, a plurality of cascaded radiation responsive voltage rectifiers, a plurality of capacitors each serially-connected between corresponding electrodes of successive ones of said cascaded rectifiers, a plurality of resistors each serially-connected with two of said capacitors, means for deriving a multiplied rectified output voltage between one of said rectifiers and said source, and means for predeterminately irradiating said rectifiers to control the conductivity thereof.

2. A voltage multiplying rectifier circuit comprising, in combination, a source of alternating potential, a plurality of cascaded radiation responsive voltage rectifiers, a plurality of capacitors serially-connected between successive ones of said cascaded rectifiers, means for deriving a multiplied rectified output voltage between one of said rectifiers and said source, and means comprising a radiation source and separate radiation conduits from said radiation source to said rectifiers for predeterminately irradiating said rectifiers to control the conductivity thereof.

3. A voltage multiplying rectifier circuit comprising, in combination, means for connecting said circuit to a source of alternating potential, a plurality of radiation-responsive voltage rectifiers, a plurality of capacitors, means serially connecting a first of said rectifiers and a first of said capacitors in shunt with said source, an impedance device, means serially connecting said impedance device and a second of said capacitors in shunt with said first rectifier, means serially connecting a second of said rectifiers and a third of said capacitors in shunt with said impedance device, means for deriving a rectified output voltage between said second rectifier and said source, connecting means and radiation means for predeterminately irradiating said rectifiers to control the conductivity thereof.

4. A voltage multiplying rectifier circuit comprising, in combination, a source of alternating potential, a plurality of cascaded radiation-responsive voltage rectifiers, a plurality of ca-

pacitors, means serially connecting a first of said rectifiers and a first of said capacitors in shunt with said source, a resistor, means serially connecting said resistor and a second of said capacitors in shunt with said first rectifier, means serially connecting a second of said rectifier and a third of said capacitors in shunt with said resistor, means for deriving a rectified output voltage between said second rectifier and said source, and radiation means for predeterminately irradiating all of said rectifiers to control the conductivity thereof.

5. A voltage multiplying rectifier circuit comprising, in combination, a source of alternating potential, a plurality of cascaded rectifying photocells, a plurality of capacitors, means serially connecting a first of said photocells and a first of said capacitors in shunt with said source, a resistor, means serially connecting said resistor and a second of said capacitors in shunt with said first photocell, means serially connecting a second of said photocells and a third of said capacitors in shunt with said resistor, means for deriving a rectified output voltage between said second photocell and said source, and radiation means for predeterminately irradiating said photocells to control the conductivity thereof.
